UNITED STATES PATENT OFFICE.

THOMAS H. HULBERT, OF MINNEAPOLIS, MINNESOTA.

SELF-CLOSING HATCHWAY.

SPECIFICATION forming part of Letters Patent No. 313,210, dated March 3, 1885.

Application filed June 20, 1884. (No model.)

To all whom it may concern:

Be it known that I, THOMAS H. HULBERT, a citizen of the United States, and a resident of Minneapolis, Hennepin county, and State 5 of Minnesota, have invented certain new and useful Improvements in Self-Closing Hatch-Covers, of which the following is a specification.

My invention relates to that class of shafts 10 or hatchways in which an elevator car or platform ascends and descends, and in which the covers are operated by said car, and is especially useful in preventing drafts of air and spread of flame in case of fire, while at the 15 same time, and during the active use of the elevator, the openings at the several floors are kept covered, avoiding loss of life by persons falling therein. I provide two flexible covers or aprons of fire-proof material fastened 20 a slight distance under the edges of the floor, and reaching from opposite sides of the hatchway and meeting in the center, and together covering the opening. Two strong tensional springs, attached to the forward edges of the 25 covers, at the corners, draws them forcibly together, extended across the opening, but with liberty of moving back to allow the elevator-car to pass. These flexible doors gradually droop or bag as the elevator approaches, and 30 when it is passing they are completely looped or collapsed against the sides of the hatchway, occupying but little space, and after the elevator has passed they again gradually extend.

The mechanism by which I accomplish the 35 easy opening of the covers, their retention against the sides, and easy closing again is comparatively simple and entirely automatic, and is operated by the elevator-car in its travel 40 up or down the shaft. I provide four arms or levers slightly curved, preferably, and of sufficient length, extending upward and backward from and supporting the forward edges of each set of doors, and attached at their upper 45 ends in proper bearings to the sides of the shaft. These levers are attached at their lower ends to two bars forming the front edges of their respective covers in reasonably accurate 50 bearings, allowing the partial rotation necessary, but avoiding cramping by one portion of either door getting ahead of the other. I

provide also a set of almost similar levers below, but extending backward or in the opposite direction. They are mounted at their lower ends on bearings at the sides of the 55 shaft, but at their upper ends each embraces, with a fork or slot, the front edges of the door, thus giving liberty of considerable play. The elevator-car in its ascent and descent rubs against these levers, forcing their ends apart, 60 and thus drooping or bagging the flexible covers against the sides of the shaft. At the corners of the elevator-car which operates the levers, I provide anti-friction rollers and vertical ways therefrom along the sides, against 65 which the levers can bear while the elevator is passing; and I arrange a brace or lock holding the levers outward in place, excepting when the elevator is approaching, to prevent bagging of the covers if anything should fall 70 on them. On freight-elevators, where there is no frame-work, I attach a rigid frame, or as many bars as there are levers reaching up from the platform, to operate said levers.

The accompanying drawings form a part of 75 this specification, and represent what I consider the best means of carrying out my invention.

Figure 1 is a central vertical section of part 80 of an elevator-shaft having my improved doors and mechanism, the car being represented as ascending and having almost reached the level of the floor. Fig. 2 is a central vertical section corresponding to Fig. 1, but at right angles thereto. Fig. 3 is a plan view of the 85 hatchway, showing the covers as closed across the opening. Figs. 4 and 5 represent details detached and on a larger scale, Fig. 4 being a section of my fire-proof cover attached to the floor, showing the construction I consider most 90 desirable; Fig. 5, a perspective view of part of an apron or cover, the front bar or slat thereof, and the upper lever attached thereto. Fig. 6 represents a modification, and is a side view of my improved hatchway, in which each 95 cover is of only two pieces, hinged at the center, and in which the levers are practically straight instead of curved.

Similar letters of reference indicate like 100 parts in all the figures.

A A are the flexible covers; B B, the sup- 100 porting-levers, extending upward and hinged

to the walls in accurate bearings $b b$; C C, the corresponding levers below, hinged at cc to the wall or sides D of the shaft, and embracing in the slots $c' c'$, in the upper ends thereof, the 5 cross-bar or front portion, A', at the corners.

5 D' D' are the several floors, and A² A² the edge of each cover, which is hinged or attached thereto at D² D², with liberty of swinging downward.

10 E E are the tensional springs attached at the sides of the front bar, A', of each cover.

G represents the elevator-car having the anti-friction rollers G' and ways g, which operate the levers, and against which they bear 15 when the elevator is in the vicinity.

H is the lock or brace, having a rule-joint or other provision for holding the covers positively extended, except when the elevator is approaching; and h h', the rod and pin, connected thereto in such manner that the elevator-car in its traverse toward this floor will 20 trip and unlock the brace.

In operation, as the elevator-car approaches from below, the pin or lever h' is moved by 25 the roller G' on the side of the car, which liberates and holds the lock H in this position. The rollers G' now begin to bear on the lowest and gradually-inclined surfaces of the four levers C, prying them at first very slowly and 30 then more swiftly apart, and at the same time sagging or opening covers A A until the top of the car has reached the level of the floor, when the springs E E are fully extended and the hatch completely open. As the car continues to ascend the adjacent parts rub against 35 the ways g until the floor-level has been passed, when the covers A and all the levers gradually take their former closed and extended position. When the car is delivering its freight 40 at the next floor, the hatch at this will be closed, or nearly so.

The curved form of my levers B and C insures the more gentle commencement of the opening movement and prevents the shock 45 and jar which would be more likely to occur if the levers were straight, and which in other forms of automatic hatch-covers is so annoying and wearing on the parts.

All the parts of my apparatus are of thin 50 and light dimensions, are of metal, and thus fire-proof. The covers swing free, moving independent of ways or tracks from the floor, and always under tension, thus avoiding danger from cramping, and withal the whole is 55 practically noiseless.

Modifications may be made without departing from my invention. At the other floors than the top and bottom two rods, h, and levers h', for unlocking the brace H, will be necessary, one set below, as shown in Fig. 1, and the other above, being operated by the car in its descent above the levers B, as will be obvious. I can, if found desirable in any case, support the covers A on the lower levers, C, 60 forming the bearings for the rods A' therein, and having the upper levers, B, provided with 65

the slots. I can use other forms of material than slats for the flexible covers C—such as woven-wire bands or tape, or overlapping strips like a shutter. In some cases it will be 70 advantageous to arrange the tensional springs E from each bar A' across to the other side, or to projections from the side walls, by which four springs will be used at each floor instead of two, so that it will not be so great a strain 75

on them, and so that both covers will be uniformly urged to their fully-extended position, even if one should lag or catch. The anti-friction-rollers G' can be dispensed with, and the ways g well lubricated, or the moving car 80

operate the levers B and C. I can provide tensional springs from below the sides of the hatchway to the middle slats of each cover, to insure their bagging or doubling at the right point; or I can provide weights on the center 85

slats for the same purpose; but I do not now deem this will be necessary. I propose in some instances, where the floors of the building are somewhat close together, to shorten 90

the levers as it may be found necessary; but this will increase the relative rise and fall of the meeting edges of the covers A'; and to obviate this I will provide slots in the ends of 95

the upper as well as the lower levers, by which each will take half of the vertical motion, as will be obvious. I may make each cover A A, 100

as shown in Fig. 6, of but two wide sections, or what would really be of two slats joined or hinged at their meeting edges, and provided, as in their other forms, with the extending 105

springs E E, so that when the elevator is passing they are folded against each other at each side, occupying but very little space. It will be 110

obvious that the covers A A can be arranged so as to fold upward instead of downward, if such should be found desirable in any instance. I can make all the levers B and C straight, as 115

shown in Fig. 7, which construction will avoid any protruding of portions outside the line of the shaft, and will not require any ways at 120

the side of the elevator-car, as the levers will always bear against the rollers at the edges. I can use weights, properly connected with 125

ropes and pulleys, to draw the covers into the extended position, instead of the spring E; and instead of the arms h' for the elevator to trip in unlocking the brace H, which may be liable to get out of order by the sudden shocks, I can provide inclined surfaces or levers which 130

will receive the motion of the moving elevator gradually. In some instances, where it may be objectionable to have the meeting edges rise and sink much when moving back and forward, I can have the levers B and C longer, being straight and perpendicular, a considerable portion only being acted on by the elevator at the portions near the covers A.

I have described the covers and levers as of metal; but if, for economy or other reason, a builder should desire it, I can make the parts 135 of wood, canvas, or other material treated with a fireproofing substance, or without such

treatment. In some situations—such as where a brick wall forms the immediate face of one side of the shaft—I can use one large cover, A, with its levers B and C and springs E all 5 reaching across to the opposite side, and, when the elevator approaches, folding or looping back all at one side of the shaft. I can, if desired, make the springs E to urge the covers together by a pushing instead of a pulling 10 force, in which case I would still retain the advantage of a continual tension on all the parts.

I claim as my invention—

1. In an automatic hatch-closing device, the 15 flexible covers A A, supported at their forward and rear edges, adapted to loop or fold at the sides of the opening, with provisions for extending the same across, substantially as described.
- 20 2. In an automatic hatch-closing device, the levers B B and C C, supporting and controlling covers A A, and adapted to be operated by the moving car, as and for the purposes herein specified.

3. In an automatic hatch-closing device, the 25 lock H and operating parts, in combination with the levers C, and adapted to be tripped by the elevator; as and for the purposes herein specified.

4. The supporting and operating levers B 30 and C, of such curved outline that the elevator in its motion will impinge on a slight and gradually-increasing angle, in combination with such elevator and with the folding covers A A, as and for the purposes described. 35

5. In an automatic hatch-closing device, the combination of the closing means E with the looping-covers A A' A² and levers B and C, the whole operating together, as and for the 40 purposes herein specified.

In testimony whereof I have hereunto set my hand, at Minneapolis aforesaid, this 9th day of June, 1884, in the presence of two subscribing witnesses.

T. H. HULBERT.
